KEYBOARD LOCKING MECHANISM FOR
LAUNDRY LISTING MACHINESWilliam John Keuper, Cincinnati, Ohio, assignor
to The National Marking Machine Company,
Cincinnati, Ohio, a corporation of Ohio

Application September 23, 1946, Serial No. 698,666

19 Claims. (CL 101—110)

1

My invention relates to an improved keyboard locking mechanism for laundry listing machines and has to do, more particularly, with an interlock that compels the operator to reset the type wheels to normal, following a printing operation, before setting up for the printing of a new list. The present application is a continuation-in-part of my pending application, Serial No. 677,189, filed June 17, 1946, for laundry listing machine.

The principal object of my present invention is to provide a locking mechanism for the keyboard of a laundry listing machine of such a nature that, when the operator initiates a printing operation to print a laundry list, the keyboard will be locked so that none of the keys can be operated and this lock will only be released by a resetting operation, to restore all displaced type wheels simultaneously to their normal positions.

A further object of my invention is to provide such a keyboard locking mechanism, in which the keyboard lock will not be released unless the resetting shaft is given a complete forward stroke, sufficient to return all displaced type wheels to their normal positions.

Another object of my present invention is to provide, in connection with such keyboard locking mechanism, a signal that will be operated as soon as the lock is applied, will continue to operate as long as the lock is effective, and will cease operation when the lock is released, thereby informing the operator that the keyboard is locked.

Further objects, and objects relating to details of construction and economies of operation, will appear from the detailed description to follow. In one instance, I have accomplished the objects of my invention by the devices and means described in the following specification. My invention is clearly defined and pointed out in the appended claims. A machine constituting a preferred embodiment of my invention is illustrated in the accompanying drawings, forming a part of this specification, in which:

Fig. 1 is a view in front elevation of a laundry listing machine embodying my invention.

Fig. 2 is a view of said machine in left side elevation.

Fig. 3 is a vertical sectional view through the central portion of said machine.

Fig. 4 is a fragmentary, sectional view taken substantially on the line 4—4 of Fig. 2.

Fig. 5 is a vertical, sectional view, showing the means for operating the resetting shaft and the means for opening the normally-closed switch when the resetting shaft is rotated to resetting position, and

2

Fig. 6 is a wiring diagram showing the electric circuits controlling the keyboard locking mechanism and the signal.

In the drawings, the same reference numerals refer to the same parts throughout the several views and the sectional view (Fig. 4) is taken looking in the direction of the arrows at the ends of the section line.

Referring to the numbered parts of the drawings, I have illustrated my invention as embodied in a laundry listing machine such as the one fully illustrated and described in my pending application for U. S. Letters Patent, Serial No. 677,189, filed June 17, 1946, for laundry listing machine and, in the drawings of the present application, I have indicated parts identical with those shown in said pending application, Serial No. 677,189, by the same reference numerals that were used therein to indicate such parts. Said laundry listing machine comprises a pair of side frames 20 connected together, at the bottom, by the transverse bars 21, near the top center, by the transverse shaft 22 and, near the front lower portion of the keyboard, by the transverse shaft 23. A casing 24 is applied to the side frames and covers the back and front of the machine, extending from a point near the rear cross bar 21 to the upper front of the machine, at the upper edge of the keyboard. The keyboard frame 25 is mounted between the front portions of the side frames 20, being pivotally mounted on the transverse shaft 23 carried by said side frames. The keyboard frame 25 has the rearwardly directed flanges 26, at the sides thereof.

Mounted on the keyboard frame 25 are sixty operating keys 34, arranged in six rows of ten keys each. One of these keys 34 is assigned to each of the classifications of articles likely to be met with in a bundle of laundry. For instance, one of the keys 34 is assigned to shirts, another to socks, one to tablecloths, another to pajama tops, another to pajama pants, one to bed-spreads, another to pillow cases, another to sheets, and so on. It will be noted that these sixty keys 34, arranged in six rows, are in staggered relation to each other, so as to give room for the operating connections. Each key 34 will bear on the key top a legend, indicating the class of article to which it is assigned. Fixed parallel horizontal shafts 35 are provided, one for each row of keys 34, the ends of said shafts being anchored in the side flanges 26 of the keyboard frame. Keys 34 of the upper row have stems 38 that are rigidly fastened to the forwardly-extending necks 301 of cams 300, pivotally mounted on the upper shaft 35, and the

keys 34 of the remaining rows have stems 37 pivoted on the shafts 35 provided for those rows of keys. Interspersed between the ten cams 300 on the upper shaft 35, which cams are provided for the upper row of keys and directly connected thereto, there are fifty cam members 300, also pivotally mounted on upper shaft 35, one of these fifty cam members being provided for each of the keys 34 in the remaining rows of keys. The cam members 300, for the rows of keys below the upper row, also have forwardly-extending necks 301, to which the upper ends of links 43 are pivotally connected. The lower end of each link 43 is pivotally connected, by a pin 45, to one of the key stems 31 of the keys of the rows below the upper one. The key stems 38 and 37 extend forwardly from the pivot shafts 35, through slots 36 provided in the keyboard frame 25. It will be noted that each of the key stems 38 and 37 may be rocked, either clockwise or counterclockwise, about its pivot shaft 35. The corresponding cam member 300 will be rocked clockwise or counterclockwise about the upper pivot shaft 35, depending upon the direction in which the corresponding key stem is swung. The cams 300 correspond to the cam extensions 39 and the cam members 40 of my said application, Serial No. 677,189, but are of somewhat different construction for the purpose of my present invention, as will be explained herein-after.

Shaft 50 is carried by the rearwardly-directed flanges 26 of the keyboard frame, extending from one of these flanges to the other, and forms the support for the mechanisms for advancing and returning the type wheels, as the several keys 34 are rocked in one direction or the other. Sixty of these mechanisms are provided, one for each of the keys 34. Each of these mechanisms includes a pair of bell cranks 51 and 52, pivotally mounted on the shaft 50, said bell cranks having the forwardly-extending arms 53 and 54, between which the corresponding cam member 300 is interposed, as shown in Fig. 3. A spring 55 has its ends connected to the arms 53 and 54 and tends to rock the upper bell crank 51 clockwise, and the lower bell crank 52 counterclockwise, about shaft 50, so as to hold the arms 53 and 54 in engagement with the cam member 300. Bell crank 51 has a pawl-carrying arm extending upwardly, on which a feed pawl 57 is pivoted at 56. Bell crank 52 has a pawl-carrying arm extending downwardly, to which a return pawl 59 is pivotally connected at 58. The ends of spring 60 are connected, one to the pawl 57 and the other to the pawl 59, and this spring tends to rock the pawls toward each other until they engage the stop shoulders 51' and 52', provided on the bell cranks 51 and 52, respectively.

A horizontal resetting shaft 46 is rotatably mounted in the side frames 20 of the machine. Journaled on the resetting shaft 46, there are sixty feed gears 47, one for each of the keys 34. Each feed gear 47 has a laterally-projecting stud 48 and another laterally-projecting stud 49 (see Fig. 3). Each feed gear 47 is in line with the corresponding feed pawl 57 and return pawl 59, arranged to be actuated by the key 34 that corresponds to the feed gear, and, when the key 34 is rocked clockwise, the corresponding cam 300 will likewise be rocked clockwise, the corresponding bell crank 51 will be rocked counterclockwise and the pawl 57 carried thereby will be caused to engage a tooth of the corresponding feed gear 47 and advance that feed gear one

step. However, if a key 34 be rocked counterclockwise about its pivot on shaft 35, the corresponding cam 300 will likewise be rocked counterclockwise, and this will cause the return pawl 59 to engage the corresponding feed gear 47 and move that gear one step in the reverse direction, that is, return said gear one step. There is a detent spring 61 for each of the gears 47, engaging the periphery thereof, these detent springs being mounted on a transverse shaft 62, the ends of which are mounted in adjusting brackets 63, pivoted at 64 on the side frame members 20. Each bracket has an elongated slot 65 receiving an eccentric portion 66 on an adjusting screw 67.

Mounted on the shaft 68, which extends transversely of the machine between the side frame members 20, there are sixty type wheels 69, one for each of the keys 34 of the keyboard. Each type wheel meshes with the corresponding feed gear 47 and, like that gear, has forty teeth. These type wheel teeth, beginning with the tooth 70 and running counterclockwise (Fig. 3), have type for printing the numerals "1," "2," etc., up to and including "37." The teeth numbered 71 do not have any type thereon and are blank, and, when a type wheel is positioned so that tooth 71 is at the printing line, no numeral printing will result and the type wheel is in its normal, non-printing position. The teeth numbered 71' are also blank, having no type thereon.

Journaled on a transverse shaft 72, which extends between the two side members 20 of the frame, are sixty printing arms 73, one for each of the keys 34. Each printing arm has a rearwardly-extending ear 74, a cam notch 75 near the lower end thereof, and a foot 76. A printing plate 77 of channel-shaped formation, and having type on the lower surface thereof for printing the name of the class of article to which the corresponding key is assigned, is detachably mounted on the foot 76 of each printing arm. The printing plate has notches 78 in the side walls thereof, which receive a pin 79 on the foot of the printing arm, and there are cam notches 80 at the rear of the printing plate, which are engaged by a spring 81, fastened in a slot 82 in the lower end of the printing arm.

One end of a spring 89 is connected to the upper end of each printing arm 73, above the pivot shaft 72 thereof, and the other ends of the springs 89 are connected to a spring bar 90, carried by and extending between the side members 20 of the frame. These springs 89 tend to swing the printing arms 73 to printing position, in which the printing plates 77 are in position to print the names of the classes of articles assigned thereto. The printing position of the printing arm 73 is determined by the engagement of the notch 75 with a transverse rod 83. A comb 87 extends forwardly and upwardly from the rod 83 and is provided with slots, one for each of the printing arms 73, in which said arms work. This comb keeps the printing arms properly spaced. A housing 88, formed of sheet metal, is carried by the side members 20 of the frame and extends across the lower front portion of the machine opposite the positions occupied by the lower ends of the printing arms and, when the printing arms are moved to non-printing position, they move back within this housing 88.

At the upper end of each printing arm 73, a selector member 91 is pivoted to the ear 74 of the printing arm, by the pin 92. This selector

member has a rearwardly-extending finger 93, normally lying in the path of the pin 49 on the corresponding feed gear 47. Each selector member 91 also has a forwardly-extending finger 94 and an oblong slot 95, concentric with pin 92 and receiving the shaft 72. A spring 96, mounted in the upper end of each printing arm 73 above the pivot shaft 72, engages the upper edge of the corresponding selector member 91 and tends to rock it clockwise about pin 92. When a feed gear 47 is displaced from its normal non-printing position, the stud 49 is removed from the finger 93 of the corresponding selector member, and permits the spring 96 to rock that selector member clockwise, so as to move the forwardly-extending finger 94 out of the path of a pick-up ledge 97, attached to a rock shaft 98, which is journaled in the side members 20 of the frame. Two springs 100, one at each side of the machine, connected, at their upper ends, to the pick-up ledge 97 and, at their lower ends, to pins 101 carried by the side frame members 20, yieldingly hold the pick-up ledge in its normal non-selecting position, against the stop pins 99 carried by said side frame members 20.

A shaft 102 is fixed in the side members 20 of the frame and extends transversely of the machine. A pair of platen-operating or printing levers is journaled on shaft 102, each lever having an upwardly and rearwardly-extending operating arm 103 and a forwardly and downwardly-extending platen-carrying arm 104. Springs 105, anchored at their rear ends to the side members 20 of the frame and secured at their forward ends to the arms 103, tend to rock the levers, of which arms 103 form a part, counterclockwise and thus tend to counter-balance the weight of the platen and associated parts. A base 106 is carried by the forwardly-extending arms 104 of these two levers, the base having downwardly-extending ears 107, at the ends thereof, which ears are pivoted on pins 108 carried by the arms 104. A platen 109, which may be of rubber or like resilient material, is carried by the base 106, to which there is also secured a sheet metal platen extension 110, extending forwardly therefrom and having a bar 111 adjustably mounted thereon to serve as a guide or abutment, against which the right-hand edge of the blank or form is placed to position it properly on the platen for printing the numbers and names of the articles in the proper place on the laundry list. Each arm 104 of the printing levers has bearings 112, in which adjusting screws 113 are mounted, said adjusting screws bearing against bosses 114 on the bottom of the base 106. The upper end of each arm 103 is forked and carries a follower roller 115, which engages a cam 117 fast on a shaft 116 journaled in the side members 20 of the frame, and having an operating crank 118 fast thereto, on the left-hand side of the machine. When the shaft 116 is given a revolution counterclockwise by turning the crank 118, the high spots of cams 117 engage rollers 115 and rock the printing levers counterclockwise, bringing the blank supported on platen 109 against the inking ribbon, which is interposed between it and the type wheels 69 and printing plates 71 at printing position, so as to make an imprint on the blank supported on platen 109. When the high spots of cams 117 pass out from under the rollers 115, the weight of the platen and its associated parts returns them to the normal position, shown in Fig. 3.

The cams 117 also act on the follower rollers

117a of the selecting mechanisms for the printing arms. At each side of the machine, there is a toggle mechanism including a rocker member 119, pivoted on a stud 120 carried by the adjacent side member 20 of the frame. This toggle mechanism, which is not shown herein but is fully described and illustrated in my pending application, Serial No. 677,189, provides a means for rocking a cam which engages a follower roller 130, carried by an arm 131, fastened on one end of the rock shaft 98, to which the pick-up ledge 97 is fixed. When the rocker member 119 is swung clockwise from the position shown in Fig. 3, arms 131 will be rocked clockwise against the tension of springs 100, thus causing the pick-up ledge 97 to engage the fingers 94 of selector members 91 in selecting position, and rock the corresponding printing arms 73 to carry them and printing plates 71 away from printing position. 20 A transversely-extending locking rod 132 extends between and is carried by the rocker members 119 and, when these rocker members are swung clockwise from the position shown in Fig. 3, the locking rod 132 will be swung into the space between teeth of the gears 47, and lock these gears and the type wheels against movement during the printing operation. Each rocker member 119 also has a laterally-extending flange (not shown), which cooperates with certain parts that will be described in connection with the resetting mechanism.

The operator may print as many lists as he desires from a given setup, but it will be necessary to reset the mechanism to normal before 35 setting up for the printing of a different list, representing the contents of a different bundle. This may be accomplished by rotating the resetting crank 136 at the right-hand side of the machine. Referring to Fig. 5, this crank is carried 40 by a hub 137 fast to a pinion 138, which is journaled on a stud 139 carried by the right-hand side member 20 of the frame. Pinion 138 meshes with a pinion 140 having an equal number of teeth, the hub of which is fast to the resetting shaft 46. Thus, rotation of the resetting crank 136 rotates pinion 138 in one direction, and pinion 140 in the opposite direction, which motion of pinion 140 is transmitted to the shaft 46. Sixty 45 resetting discs 148 are provided, one for each of gears 47, said discs being mounted on the resetting shaft 46, interspersed between gears 47, and each disc being keyed to that shaft by a key 150 (Fig. 3). Each resetting disc 148 has a projection 149, which normally lies in front of 50 the stud 48 on the corresponding gear 47. The operator, by means of crank 136, rotates shaft 46 to the limit of movement in the clockwise direction (Fig. 3), which causes the projections 149 on the resetting discs to engage the rear sides of pins 48 and bring all the pins to the 55 normal position shown in Fig. 3. The operator, then, reverses the direction of rotation of crank 136 and returns that crank and the resetting discs to the normal position shown in Fig. 3, in 60 which the projections 149 lie in front of the pins 48. The resetting position of shaft 46 is that in which the projections 149 of the resetting discs 65 will be in engagement with the rear of the pins 48, when the feed gears 47 and type wheels 69 are in the normal, non-printing position.

Pinion 140 has a member 144 fast thereto, provided with a flange 151, in which a notch 152 is formed (Fig. 5). When the resetting shaft 46 is in its normal position, shown in Fig. 3, and 70 the right-hand rocker member 119 is rocked

clockwise by its cam 111 to select the printing plates for an imprint, the laterally-extending flange previously mentioned (not shown) on said rocker member 119, moves into the notch 152 and against the front wall of that notch. Just as soon as resetting shaft 46 is turned in the clockwise direction, at the beginning of the resetting operation, the front wall of notch 152 engages said laterally-extending flange on rocker 119, and rocks member 119 counterclockwise, thus restoring the toggle mechanism to the normal position and causing the cams acting on the follower rollers 130 to move away therefrom, so that springs 190 can rock shaft 98 and the pick-up ledge 97 to the position shown in Fig. 3, in which position springs 190 maintain the ledge 97 against the stop pins 99. This counterclockwise movement of the rocker members 119, also, removes the locking rod 132 from between the teeth of feed gears 47, thus releasing said feed gears and type wheels at the beginning of the resetting stroke.

Member 144 has integral therewith a radially-extending finger 153, which lies against the lower side of stop 154 (Fig. 5), when the resetting shaft 46 is in normal position. At the end of the first half of the resetting stroke, when the resetting shaft is in resetting position, finger 153 lies above the stop 154, which limits the movement of the shaft 46 in the forward direction.

Referring to Figs. 1, 2 and 3, hubs 172 are journaled on studs 173, carried by side members 20 of the frame in line with the axis of shaft 192. The legs 174 of a bail 175, which extends across the platen extension 110, are fixed in the hubs 172. This bail may be made of a translucent plastic material having marks thereon to permit the operator to align the form properly on the platen 109 and platen extension 110. Springs 176 are connected, at their upper ends, to the hubs 172 and, at their lower ends, to pins 116 on the side frame members 20 and tend to rock the bail 175 so as to carry it against the form mounted on the platen.

It is desirable, in connection with a laundry listing machine of the type described above, to compel the operator, after the initiation of a printing operation, to restore all of the type wheels to zero, before any of the keys of the keyboard can be operated to set up a new list. In accordance with my present invention, this is accomplished by providing a normally inactive locking device for locking the means for selectively advancing the type wheels, or the keyboard, which will be rendered active by the operation of the printing means, and will be restored to normal, inactive position by operation of the resetting means. In my said pending application, Serial No. 677,189, of which the present application is a continuation-in-part, the operation of the printing shaft 116 through cams 111 causes the rocker members 119 to rock clockwise, carrying the locking rod 132 into engagement with spaces between the teeth of gears 47. This locks gears 47 and type wheels 69 against movement, and locks the keys 34 on the keyboard against all except such limited movement as would bring the feed pawls 51 or the return pawls 59 into engagement with teeth of the feed gears 47. However, in the machine shown in my said pending application, the rocker members 119 are swung counter-clockwise at the very beginning of a resetting stroke, so that the feed gears 47, the type wheels 69 and the keys 34, in that machine, might be unlocked for op-

eration when the resetting shaft is given only a partial forward stroke, and one insufficient to restore all displaced type wheels to their normal non-printing positions. In the machine of my present application, I have provided a keyboard locking mechanism of such nature that the keys of the keyboard, having been locked by the operation of the printing means, will not be unlocked until a complete forward stroke of the resetting shaft 46 has been made to the resetting position, which insures that all the displaced type wheels 69 will be restored to normal position before the keyboard is unlocked.

As stated above, I have provided a plurality of cams 300 journaled on the upper shaft 35. These cams 300 correspond to cam extensions 39 and cams 40 of my said pending application, Serial No. 677,189, and cooperate with the bell crank levers 51 and 52 in the same way that said cams cooperated with said levers. There are sixty cams 300, one for each of the operating keys 34 of the machine, mounted side by side on the upper shaft 35. Each cam 300 has a forwardly-extending neck 301. The necks 301 of the cams assigned to the upper row of keys 34 are rigidly connected to the stems 38 of said keys, and the necks 301 of the cams assigned to the other keys of the keyboard are each pivotally connected to the upper end of a link 43, the lower end of which is pivotally connected, as at 45, to the stem 37 of the key 34 to which the corresponding cam is assigned. Each cam 300 has a T-shaped slot therein, the head portion 302 of which is concentric with the axis of the upper shaft 35 about which the cams 300 are rockable, and the stem portion 303 of which slot is radial of said axis. Sockets 304 (Fig. 4) are formed in the side frame members 20 of the machine and bores 305, of smaller diameter, communicate with the bottoms of said sockets. Plungers 306 are slidably mounted in the sockets 304 and have tail portions 307, of smaller diameter, slidible in the bores 305. Springs 308, positioned in the sockets 304 surrounding the tail portions 307 of the plungers, are interposed between the bottoms of said sockets and the shoulders between the tail portions 307 and the bodies of plungers 306, and tend to project said plungers from said sockets. Each plunger 306 is provided with a head portion 309, through which extends a locking rod 310 that is fastened to said head portions and extends through the T-shaped slots in the cams 300. Brackets 311, fastened to the side frame members 20, carry adjustable stop screws 312 that are engaged by the head portions 309 of the plungers, and limit the movement thereof under the pressure of springs 308. When the plungers 306 are in their projected positions, with the heads 309 engaging the stop screws 312, the locking rod 310 will lie in the head portions 302 of the T-shaped slots in the cams 300, so that said cams may rock freely about the axis of the upper shaft 35. A collar 313 is fast to each end of the locking rod 310, outside the frame, and is provided with an ear that is received in the forked end 314 of a solenoid core 315, the core being pivotally connected to the ear of said collar. The cores 315 work in solenoids 316, mounted on the side frame members 20, and, whenever these solenoids are energized, the cores 315 will be drawn into them, thus moving the locking rod 310 into the stem portions 303 of the T-shaped slots, and locking the cams 300 against movement, thereby locking the keys 34 of the keyboard against operation.

A pair of contacts 317 (Figs. 3 and 6) are mounted by a suitable bracket on one of the side members 20 of the machine frame, in position to be engaged by a contact 319 carried by a bracket 318, fixed to the adjacent printing lever 104. This is a normally-open switch but, when the lever 104 is rocked counterclockwise by the rotation of shaft 116 and cam 117, contact 319 will engage contacts 317 and close this normally-open switch. This will occur at the 10 end of the printing stroke.

A normally-closed switch 320 is adjustably mounted on one of the side members 20 of the frame by means of a bracket 188, pivotally mounted on the stud 187 and adjustable by means of the eccentric pin 189 working in the slot 189 of the bracket. This switch 320 is normally closed and is provided with an operating button 321, pressure on which opens the normally-closed switch. As shown in Fig. 5, this switch is so located that, when the resetting shaft 46 is turned to resetting position, in which position finger 153 will lie above the stud 154, the end of finger 153 will engage and depress the operating button 321 to open the normally-closed switch 320.

A signal light 335 is mounted on the front of the machine near the lower right-hand corner thereof. The printing lever 104 may carry an adjustable stop screw 338, the head of which is adapted to make contact with a block 339 carried by the frame of the machine, to limit the rocking movement of the lever 104 in the clockwise direction.

The wiring diagram, Fig. 6, shows the electric circuit controlling the solenoids 316. A lead 322, connected to one side of a source of suitable electric current, is connected by the branch leads 323 to one end of the winding of each solenoid 316. The other ends of said windings are connected by the branch leads 324 to a lead 325, which is connected by lead 326 to the movable contact member 327 of a normally-open relay switch having an operating coil 328. The fixed contact, with which said movable contact 327 cooperates, is connected by lead 329 to the other side of said source of current. It will be obvious that, when the normally-open relay switch 327 is closed, current will be supplied to the solenoids 316, which will be energized to move the locking rod 310 to locking position against the pressure of springs 308. As stated, the relay switch 327 is normally open but, when the operating coil 328 thereof is energized, the switch 327 will be closed. The lead 322 is connected by lead 330 to one end of the operating coil 328 of the relay, the other end of said coil being connected by lead 331 to one of the fixed contacts 317 of the normally-open switch previously referred to. The other fixed contact 317 of said switch is connected by the lead 332 to the lead 329 connected to the other side of the source of current. This constitutes a starting circuit and it will be obvious that the closing of the movable contact 319 on the fixed contacts 317, when the printing lever 104 is rocked in the printing operation, will result in the energizing of the operating coil 328 of the normally-open relay and, hence, in the closing of said relay, which closes the circuit to the solenoids 316 and energizes them. The normally-open switch 319-317 will open again as the printing lever returns to normal at the close of the printing operation, and this would result in the deenergizing of the operating coil 328 and the consequent deenergizing of the

solenoids 316, but for the holding circuit that I have provided.

This holding circuit comprises a lead 334 connecting the lead 325 with one of the terminals 5 of the normally-closed switch 320, the other terminal of that switch being connected by the lead 333 to the lead 331 to one end of the operating coil 328. This holding circuit, therefore, includes the operating coil 328, the normally-closed switch 320 and the normally-open relay 327, and the operating coil 328 will be held energized and the relay switch 327 held closed as long as switch 320 is closed. However, when the resetting shaft 46 is rotated to resetting position, switch 320 is opened and that breaks the holding circuit for the operating coil 328, so that, the switch 319-317 operated by the printing lever being open, the coil 328 is deenergized and relay switch 327 opened, so that the solenoids 316 are deenergized and the locking rod 310 moves to ineffective position under the pressure of the springs 308.

The electric signal lamp 335 is connected in parallel to the solenoids 316 by lead 337, connecting one terminal of said lamp to the lead 322, and lead 336 connecting the other terminal of said lamp to lead 325. It will be evident that the electric lamp 335 will be lit as soon as the solenoids 316 are energized, and will remain lit 30 as long as these solenoids are energized, so that it acts as a signal to indicate that the keyboard is locked. The operator will know that a sufficient forward stroke to cause the lamp 335 to go out must be given to the resetting shaft 46, and such stroke will be sufficient to release the keyboard locking mechanism and permit further operation of the keys.

The operation of my improved keyboard locking mechanism for laundry listing machines 40 should be apparent from the foregoing description. Let us assume that the operator has depressed the proper keys 34 the proper number of times to set the type wheels 69 for the printing of the desired laundry list. In such setting-up 45 operation, some of the type wheels 69 will be displaced from their normal non-printing positions. A blank on which the laundry list is to be printed is placed on the platen 109 and the operator gives the shaft 116 one complete revolution, by 50 means of the crank 118 at the left of the machine. This results in the rocking of the printing levers 104 counterclockwise carrying the blank on the platen 109 against the type of type wheels at 55 printing position. The rocking of levers 104 will result in the closing of the normally-open switch 319-317. This, as we have pointed out, energizes the operating coil 328 and closes relay switch 327, which closes the circuit to the solenoids 316 and the electric lamp 335. At that time, locking rod 60 310 is moved into the stem portions 303 of the T-shaped slots, locking the cams 300 against rocking movement and locking the keys 34 of the keyboard against operation. At the same time, the lamp 335 is lit to signal to the operator 65 that the keyboard is locked. The closing of the starting circuit by switch 319-317 also resulted in the closing of the holding circuit, which includes the normally-closed switch 320. The holding circuit will remain closed, even 70 though the switch 319-317 opens at the completion of the printing operation. Therefore, the keyboard remains locked and the lamp 335 continues lit to signal to the operator the locked condition. When the operator, by means of the 75 crank 136 at the right-hand side of the ma-

chine, gives the resetting shaft 46 a complete forward stroke to resetting position, in which the finger 153 lies above the stud 154, the normally-closed switch 320 will be opened and this breaks the holding circuit, so that the operating coil 328 is deenergized and the relay switch 327 opens. This deenergizes the solenoids 316 so that the springs 308 move the locking rod 310 to its normal inactive position in the head portions 302 of the T-shaped slots, in which position the cams 300 are rockable about the axis of the upper shaft 35 and the keys of the keyboard are unlocked and can be operated at will. At the same time, the circuit to the lamp 335 is broken so that that lamp goes out.

I am aware that the keyboard locking mechanism for laundry listing machines described herein is susceptible of considerable variation without departing from the spirit of my invention and, therefore, I claim my invention broadly as indicated by the appended claims.

Having thus described my invention, what I claim as new and useful and desire to secure by Letters Patent, is:

1. In a laundry listing machine, the combination of a plurality of rotatable type wheels; means for selectively advancing said type wheels step-by-step from normal position, said means including a feed pawl associated with each of said type wheels and movable from an inactive position in which it is disconnected from its associated type wheel to an active position in which it is effective to impart a step of movement to the wheel, and a selectively rockable cam for moving its related pawl from inactive position to active position, said cam having formed therein a T-shaped slot the head of which is concentric with the axis about which the cam rocks and the stem of which is radial of the axis; resetting means for simultaneously restoring all displaced type wheels to their normal positions; printing means operable to make an imprint from said type wheels; a locking rod passing through the slots in all of said cams; means actuated by said printing means for moving said rod from the head portions of the slots into the stem portions thereof, thereby locking said cams against operation; and means actuated by operation of said resetting means for returning said rod into the head portions of said slots thereby releasing said cams.

2. In a laundry listing machine, the combination of a plurality of rotatable type wheels; means for selectively advancing said type wheels step-by-step from normal position, said means including a feed pawl associated with each of said type wheels and movable from an inactive position in which it is disconnected from its associated type wheel to an active position in which it is effective to impart a step of movement to the wheel, and a selectively rockable cam for moving its related pawl from inactive position to active position, said cam having formed therein a T-shaped slot the head of which is concentric with the axis about which the cam rocks and the stem of which is radial of the axis; a resetting shaft; means for rotating said resetting shaft to simultaneously restore all displaced type wheels to their normal positions; printing means operable to make an imprint from said type wheels; a locking rod passing through the slots of all of said cams; means actuated by said printing means for moving said rod from the head portions of the slots into the stem portions thereof, thereby locking said

cams against operation; and means actuated by rotation of said resetting shaft for returning said rod into the head portions of said slots thereby releasing said cams.

3. In a laundry listing machine, the combination of a plurality of rotatable type wheels; means for selectively advancing said type wheels step-by-step from normal position, said means including a feed pawl associated with each of said type wheels and movable from an inactive position in which it is disconnected from its associated type wheel to an active position in which it is effective to impart a step of movement to the wheel, and a selectively rockable cam for moving its related pawl from inactive position to active position, said cam having formed therein a T-shaped slot the head of which is concentric with the axis about which the cam rocks and the stem of which is radial of the axis; a resetting shaft; means for rotating said resetting shaft to simultaneously restore all displaced type wheels to their normal positions; a printing shaft; means for rotating said printing shaft to make an imprint from said type wheels; a locking rod passing through the slots of all of said cams; means actuated by rotation of said printing shaft for moving said rod from the head portions of the slots into the stem portions thereof, thereby locking said cams against operation; and means actuated by rotation of said resetting shaft for returning said rod into the head portions of said slots thereby releasing said cams.

4. In a laundry listing machine, the combination of a plurality of rotatable type wheels; means for selectively advancing said type wheels step-by-step from normal position; normally ineffective means for locking said advancing means against operation; means, including a solenoid, for rendering said locking means effective; a normally open circuit for energizing said solenoid; printing means operable to make an imprint from said type wheels; means actuated by said printing means for closing said circuit and energizing said solenoid so as to render said locking means ineffective; resetting means for simultaneously restoring all displaced type wheels to their normal positions; and means actuated by said resetting means for breaking said circuit and deenergizing said solenoid so as to render said locking means ineffective.

5. In a laundry listing machine, the combination of a plurality of rotatable type wheels; means for selectively advancing said type wheels step-by-step from normal position; normally ineffective means for locking said advancing means against operation; means, including a solenoid, for rendering said locking means effective; an energizing circuit for said solenoid; printing means operable to make an imprint from said type wheels; a relay; a normally open switch in said energizing circuit operable by said relay; means actuated by said printing means for energizing said relay and closing said switch so as to cause said solenoid to be energized and said locking means to be rendered effective; resetting means for simultaneously restoring all displaced type wheels to their normal positions; and means actuated by said resetting means for deenergizing said relay and opening said switch whereupon said solenoid will be deenergized and said locking means rendered ineffective.

6. The combination recited in claim 5 includ-

13

ing a holding circuit for maintaining said relay energized.

7. The combination recited in claim 6 wherein said means actuated by said resetting means includes a normally closed switch in said holding circuit.

8. In a laundry listing machine, the combination of a plurality of rotatable type wheels; means for selectively advancing said type wheels step-by-step from normal position; a resetting shaft; means for giving said shaft a forward and a return stroke of movement; means actuated by said shaft during the forward stroke thereof for simultaneously restoring all displaced type wheels to their normal positions; printing means operable to make an imprint from said type wheels; a device movable from a normal position to a locking position for locking said advancing means against operation; means actuated by said printing means for moving said device from normal position to locking position; and means actuated by said resetting shaft at the end of its forward stroke after all displaced type wheels have been restored to their normal positions for returning said device to its normal position.

9. In a laundry listing machine, the combination of a plurality of rotatable type wheels; means for selectively advancing said type wheels step-by-step from normal position, said means including a device associated with each of said type wheels and movable from an inactive position in which it is disconnected from its associated type wheel to an active position in which it is effective to impart a step of movement to the wheel, and a selectively operable member for moving each of said devices from inactive position to active position; a resetting shaft; means for giving said shaft a forward and a return stroke of movement; means actuated by said shaft during the forward stroke thereof for simultaneously restoring all displaced type wheels to their normal positions; printing means operable to make an imprint from said type wheels; means actuated by said printing means for locking said members against operation; and means actuated by said resetting shaft at the end of its forward stroke and after all displaced type wheels have been restored to their normal positions for releasing said locking means.

10. In a laundry listing machine, the combination of a plurality of rotatable type wheels; means for selectively advancing said type wheels step-by-step from normal position, said means including a device associated with each of said type wheels and movable from an inactive position in which it is disconnected from its associated type wheel to an active position in which it is effective to impart a step of movement to the wheel, and a selectively operable member for moving each of said devices from inactive position to active position; normally ineffective means for locking said members against operation; means, including a solenoid for rendering said locking means effective; printing means operable to make an imprint from said type wheels; means actuated by said printing means for energizing said solenoid and rendering said locking means effective to lock said members; resetting means for simultaneously restoring all displaced type wheels to their normal positions; and means actuated by said resetting means for deenergizing said solenoid and rendering said locking means ineffective to lock said members against operation.

11. In a laundry listing machine including a

14

plurality of rotatable type wheels, a plurality of operating keys one for each type wheel, advancing means for selectively advancing said type wheels step-by-step, a resetting shaft, means for rotating said shaft to resetting position to restore simultaneously all displaced type wheels to normal positions and for returning said shaft to normal position, a printing lever, and means for rocking said lever to make an imprint from said type wheels, a keyboard locking mechanism comprising the combination of a plurality of cams rockable about a common axis for operating said advancing means, one cam being connected for operation to each of said keys, each of said cams having a T-shaped slot therein the head of which is concentric with said axis and the stem of which is radial of said axis; a locking rod passing through all of said slots; means, actuated by the rocking of said printing lever, to move said rod into the stem portions of said slots; and means, actuated by the rotation of said resetting shaft from normal, to return said rod to the head portions of said slots.

12. In a laundry listing machine including a plurality of rotatable type wheels, a plurality of operating keys one for each type wheel, advancing means for selectively advancing said type wheels step-by-step, a resetting shaft, means for rotating said shaft to resetting position to restore simultaneously all displaced type wheels to normal positions and for returning said shaft to normal position, a printing lever and means for rocking said lever to make an imprint from said type wheels, a keyboard locking mechanism comprising the combination of a plurality of cams rockable about a common axis, one cam being connected for operation to each of said keys, each cam having a T-shaped slot therein the head of which is concentric with said axis and the stem of which is radial thereof, said cams when operated by said keys being adapted to actuate said advancing means; a locking rod passing through all said slots; spring means normally holding said rod in the head portions of said slots; means, actuated by the rocking of said printing lever, to move said rod into the stem portions of said slots against the pressure of said spring means; and means, actuated by rotation of said resetting shaft to resetting position, for releasing said rod to permit it to move into the head portions of said slots under the pressure of said spring means.

13. In a laundry listing machine including a plurality of rotatable type wheels, a plurality of operating keys one for each type wheel, advancing means for selectively advancing said type wheels step-by-step, a resetting shaft, means for rotating said shaft to resetting position to restore all displaced type wheels simultaneously to normal and for returning said shaft to normal, a printing lever, and means for rocking said lever to make an imprint from said type wheels, a keyboard locking mechanism comprising the combination of a plurality of cams rockable about a common axis and effective when rocked to actuate said advancing means, one of said cams being connected for operation to each of said keys, each cam having a T-shaped slot therein the head of which is concentric with said axis and the stem of which is radial thereof; a locking rod passing through all said slots; spring means normally holding said rod in the head portions of said slots; a solenoid acting when energized to move said rod into the stem portions of said slots; means, actuated by the rocking of said

printing lever, for energizing said solenoid; and means, actuated by the rotation of said resetting shaft to resetting position, for deenergizing said solenoid.

14. In a laundry listing machine including a plurality of rotatable type wheels, a plurality of operating keys one for each type wheel, advancing means for selectively advancing said type wheels step-by-step, a resetting shaft, means for rotating said shaft to resetting position to restore all displaced type wheels to normal and for returning said shaft to normal, a printing lever, and means for rocking said lever to make an imprint from said type wheels, a keyboard locking mechanism comprising the combination of a plurality of cams rockable about a common axis and adapted when rocked to actuate said advancing means, one of said cams being connected to each of said keys for operation thereby, each cam having a T-shaped slot therein the head of which is concentric with said axis and the stem of which is radial thereof; a locking rod passing through all said slots; spring means normally holding said rod in the head portions of the slots; a solenoid acting when energized to move said rod into the stem portions of said slots; a normally open switch; means, carried by said printing lever, for closing said switch upon actuation of said lever to make an imprint; a normally closed switch; a member fixed to said resetting shaft and effective to open said normally closed switch when said resetting shaft is turned to resetting position; a normally open relay; an electric circuit including a source of current, said solenoid and said relay; a starting circuit including the source of current, said normally open switch and the operating coil of said relay; and a holding circuit including said source of current, the relay, said normally closed switch and said operating coil of the relay.

15. In a laundry listing machine including a plurality of rotatable type wheels, a plurality of operating keys one for each type wheel, advancing means for selectively advancing said type wheels step-by-step, a resetting shaft, means for rotating said shaft to resetting position to restore simultaneously all displaced type wheels to normal and for returning said shaft to normal, a printing lever, and means for rocking said lever to make an imprint from said type wheels, a keyboard locking mechanism comprising the combination of a plurality of cams rockable about a common axis and adapted when rocked to actuate said advancing means, one of said cams being connected to each of said keys for operation thereby, each cam having a T-shaped slot therein the head of which is concentric with said axis and the stem of which is radial thereof; a locking rod passing through all said slots; spring means normally holding said rod in the head portions of the slots; a solenoid acting when energized to move said rod into the stem portions of said slots; a normally open switch; means carried by said printing lever for closing said switch upon actuation of said lever to make an imprint; a normally closed switch; a member fixed to said resetting shaft and effective to open said normally closed switch when said resetting shaft is turned to resetting position; a normally open relay; an electric circuit including a source of current, said solenoid and said relay; a starting circuit including the source of current, said normally open switch and the operating coil of said relay; a holding circuit including said source of current, the relay, said

normally closed switch and said operating coil of the relay; and a signal lamp connected in said electric circuit in parallel to said solenoid.

16. In a laundry listing machine including a plurality of rotatable type wheels, a plurality of operating keys one for each type wheel, means actuated by the operation of said keys for selectively advancing said type wheels step-by-step, a resetting shaft, means for rotating said shaft to resetting position to restore simultaneously all displaced type wheels to normal and for returning said shaft to normal, a printing lever, and means for rocking said lever to make an imprint from said type wheels, a keyboard locking mechanism comprising the combination of a locking device movable from normal ineffective position to an effective position, in which it locks said keys against operation; spring means normally holding said locking device in ineffective position; a solenoid acting when energized to move said locking device to effective position; a normally open switch; means carried by said printing lever for closing said switch upon actuation of said lever to make an imprint; a normally closed switch; a member fixed to said resetting shaft and effective to open said normally closed switch when said resetting shaft is turned to resetting position; a normally open relay; an electric circuit including a source of current, said solenoid and said relay; a starting circuit including the source of current, said normally open switch and the operating coil of said relay; and a holding circuit including said source of current, the relay, said normally closed switch and said operating coil of the relay.

17. In a laundry listing machine including a plurality of rotatable type wheels, a plurality of operating keys one for each type wheel, means actuated by the operation of said keys for selectively advancing said type wheels step-by-step, a resetting shaft, means for rotating said shaft to resetting position to restore simultaneously all displaced type wheels to normal and for returning said shaft to normal, a printing lever, and means for rocking said lever to make an imprint from said type wheels, a keyboard locking mechanism comprising the combination of a locking device movable from normal ineffective position to an effective position, in which it locks said keys against operation; spring means normally holding said locking device in ineffective position; a solenoid acting when energized to move said locking device to effective position; a normally open switch; means carried by said printing lever for closing said switch upon actuation of said lever to make an imprint; a normally closed switch; a member fixed to said resetting shaft and effective to open said normally closed switch when said resetting shaft is turned to resetting position; a normally open relay; an electric circuit including a source of current, said solenoid and said relay; a starting circuit including the source of current, said normally open switch and the operating coil of said relay; a holding circuit including said source of current, the relay, said normally closed switch and said operating coil of the relay; and a signal lamp connected in said electric circuit in parallel to said solenoid.

18. In a laundry listing machine including a frame, a plurality of rotatable type wheels, a plurality of operating keys one for each type wheel, advancing means for selectively advancing said type wheels step-by-step, a resetting shaft, means for rotating said shaft to restore simultaneously all displaced type wheels to normal and for re-

turning said shaft to normal, a printing lever, and means for rocking said lever to make an imprint from said type wheels, a keyboard locking mechanism comprising the combination of a plurality of cams rockable about a common axis and adapted to actuate said advancing means when rocked, one of said cams being connected to each of said keys for operation thereby, each cam having a T-shaped slot therein the head of which is concentric with said axis and the stem of which is radial thereof; a pair of plungers slidably mounted in sockets formed in said frame; a locking rod carried by said plungers and passing through said slots; spring means acting on said plungers to project them from said sockets and hold the rod normally in the head portions of said slots; means, actuated by the rocking of said printing lever, to retract said plungers into said sockets and to move the rod into the stem portions of said slots against the pressure of said spring means, and means, actuated by rotation of said resetting shaft, for releasing the last-mentioned means to permit said spring means to project said plungers and move the rod into the head portions of said slots.

19. In a laundry listing machine including a frame, a plurality of rotatable type wheels, a plurality of operating keys one for each type wheel, advancing means for selectively advancing said type wheels step-by-step, a resetting shaft, means for rotating said shaft to restore simultaneously all displaced type wheels to normal and for returning said shaft to normal, a printing lever, and means for rocking said lever to make an imprint from said type wheels, a keyboard locking mechanism comprising the combination of a plurality of cams rockable about a common axis and adapted to actuate said advancing means when

rocked, one of said cams being connected to each of said keys for operation thereby, each cam having a T-shaped slot therein the head of which is concentric with said axis and the stem of which is radial thereof; a pair of plungers slidably mounted in sockets formed in said frame; a locking rod carried by said plungers and passing through said slots; spring means acting on said plungers and normally tending to project them from said sockets and hold said rod in the head portions of the slots; a pair of solenoids having cores connected to said rod so that, when said solenoids are energized, said rod will be moved into the stem portions of said slots against the pressure of said spring means; means, actuated by the rocking of said printing lever, for energizing said solenoids; and means, actuated by the rotation of said resetting shaft, for deenergizing said solenoids.

Certificate of Correction

Patent No. 2,573,847

November 6, 1951

WILLIAM JOHN KEUPER

It is hereby certified that error appears in the printed specification of the above numbered patent requiring correction as follows:

Column 14, line 44, for "postions" read *portions*; column 17, line 21, for "means," first occurrence, read *means*;;

and that the said Letters Patent should be read as corrected above, so that the same may conform to the record of the case in the Patent Office.

Signed and sealed this 12th day of February, A. D. 1952.
